KNICKER TURN-UP SPREADER

Morris Reich, Columbus, Ohio

Application February 13, 1933, Serial No. 656,416

4 Claims. (Cl. 2—228)

The invention to be hereinafter described relates to knicker turn-up spreaders.

Knickers for men and boys have long been in use for various out door sports. More recently, they have been becoming generally worn by women in various sports. The bottoms of the legs are secured in place around the legs of the wearer by buckles and straps, elastics, knit cuffs, draw strings, buttons, etc., which grip the leg. Knickers are favored for sports wear because they are roomy and loose and give complete freedom of action. Nevertheless, the gripping of the leg by the securing means, has long been considered a draw back and an objection. By tightly closing the lower end of the knicker leg, about the leg of the wearer, circulation is interfered with, and all upward air circulation is cut off and all resulting cooling ventilation is lost, which, of course, are serious objections of the present knickers. Obviously, the addition of the securing means adds to the cost of production. Of even greater objection is total lack of length adjustment. In boys' knickers this is particularly needed. Growing children, especially, soon require lengthening of knickers. In the knickers as now obtainable on the market, there is no provision for readily changing the length.

The present invention overcomes all of the above objections and provides a simple, efficient, inexpensive construction which may be applied in minimum time, with very little labor and extremely small cost. It provides a knicker which may be quickly and easily lengthened and shortened without alterations of the knicker itself as far as cutting or shaping of the cloth is concerned. It provides an open ended, free hanging, well shaped, knicker with full ventilation and unrestricted circulation.

Applicant is thoroughly familiar with United States Patent 1,306,935, in which buttons and tabs are used to secure an upwardly turned portion. In order to more clearly disclose the construction, operation and use of the invention, reference is hereby made to the accompanying drawing forming part of the present application.

Throughout the drawing like reference characters designate the same parts in the several different views.

In the drawing:—

Fig. 1 is a side view of part of a knicker leg, with the spreaders down or inoperative;

Fig. 2 is an enlarged fragmentary detail cross-section, through one spreader in its loop;

Fig. 3 is an enlarged fragmentary view showing one spreader in plan in its loop;

Fig. 4 is a view similar to Fig. 1 with spreaders up or operative.

Fig. 5 is a cross-section on line 5—5 of Fig. 4; Fig. 6 is a longitudinal cross-section of Fig. 3; Fig. 7 is a fragmentary view similar to Fig. 5, showing a modified spreader; and,

Fig. 8 is a view similar to Fig. 4 but showing the modified spreader of Fig. 7.

The general construction as well as various types of knickers for men, women and children are all well known and, therefore, will not be illustrated or described in this application.

In order to illustrate the invention, it has been shown in the drawing as applied to a part of a knicker leg. It is applied to both legs, of course, and in the same way to each. A description of one is equally a description of the other. Consequently, only one leg will be shown and described, as that will give a full and complete disclosure of the invention. It will be understood that the invention is applicable to tubular parts of garments such as the leg or relatively large diameter sleeves, such as might be found in certain types of sport coats. It would be constructed and applied and would operate in substantially the same way for such a sleeve. Therefore, the illustration as applied to a sleeve is unnecessary in this case, that for the leg being ample.

In all cross-section views in this application, the parts have been considerably exaggerated and are out of relative proportion, for clearness. Were the relative proportions maintained, the views would be unnecessarily large.

Assume that a pair of boy's knickers is to be made with the present invention applied. The chosen piece of material is measured for length. From the end of this measurement is added approximately three and one-half inches. Or to state it a little differently, the given measurement is increased three and one-half inches, more or less. This increase provides a portion which may be properly termed the turn-up 1, which, as shown in Fig. 4 is turned or folded upwardly within the lower end of the knicker leg, when the knicker is completed. In boys' knickers this turn-up is tapered, as shown, from an approximate leg width of about twenty inches at the end of the measurement to an approximate leg width of fifteen inches at the lower end of the turn-up. It is, of course, understood, that the measurements vary somewhat within recognized limits, according to circumstances and the particular pair of knickers. This turn-up, together with the proper proportions, which are well known, gives the fullness or looseness char-

acteristic of knickers. But, the great difficulty has been to find some practical, efficient and satisfactory way of reliably permanently extending and supporting the turn-up, without fastening it to the leg of the knicker and, at the same time, to provide a very simple and thoroughly satisfactory way for length adjustment, not requiring the services of an experienced tailor. The turn-up, unsupported, would simply drop, of its own weight. In the preferred form of my invention, I accomplish these results by attaching short spreaders or supporting members 2 of whale bone, metal, fibre or other suitable material to the inner side of the turn-up and extending substantially the vertical length of the turn-up. In the drawing, I have shown four such members. With many kinds of cloth that number gives best results. With some kinds of cloth, two will be sufficient, while with others, six may be advisable. A sufficient number, according to the character of the cloth, are used to adequately spread and support the turn-up. They are, preferably, placed at equal distances apart and suitably spaced from seams and like parts. They co-operate with the cloth in the same way that fence posts co-operate with the fence wires, they keep the cloth up and extended or supported, and prevent it from sagging. Without such members, the weight of the cloth, alone, would cause it to sag down and unroll out of the bottom of the leg, between the knicker leg and the wearer's leg. With the spreaders, such sagging or unrolling is impossible. Instead, the spreaders tend to swing or rock inwardly about their lower ends. As they do, they carry the full height and width of the turn-up with them. The distance between the inside of the knicker leg and the leg of the wearer is slight. Consequently, the spread turn-up soon contacts the wearer's leg and is prevented from dropping down. Of course, only a very light, hardly noticeable, touch is all that is necessary to stop the swing of the turn-up. The spreaders, by keeping the cloth extended, or spread, prevent its rolling and in that way slipping or falling down. I have found that a width of about one quarter of an inch is very satisfactory for these spreaders, but they may vary within the discretion of the user and according to the particular circumstances or requirements of the individual case.

One very practical and acceptable way of applying these spreaders is shown in the drawing. It comprises a loop 3 stitched or sewed to the inside of the turn-up. Preferably, each loop—there is one for each spreader—extends substantially the full length, vertically, of the turn-up, from the lower edge. The loop may be open at both ends. The lower end, however, extends within the usual hem 4 at the end of the turn-up and is closed by the cloth of the hem. Of course, it may be stitched closed, if desired, though that is not necessary. In this arrangement, each spreader is simply slipped under the loop or between it and the knicker leg, just as it would be slipped into a pocket. Other, though less satisfactory ways of holding the spreaders in place would be to provide them with perforations and stitch them to the turn-up, or to form loops or pockets similar to the one above mentioned but by stitching the cloth of the side-seams of the leg to the inside of the leg. A still further way would be to line the turn-up and stitch the lining at various points to form a series of loops. Or to provide them with pockets and secure the pockets in place with snap fasteners. These several ways will be thor-

oughly understood by those familiar with the clothing business and need not be further illustrated or detailed in description.

A modification is shown in Figs. 7 and 8. Here, instead of a series of separate and independent spreaders, a single continuous spreader 5 is used. This, preferably, is a piece of heavy duck, canvas or similar stiff material. Or it may be in two or more pieces, as is most practical for the particular knickers. It is simply suitably secured to the turn-up 1 on the inside and extends as do the spreaders 2, substantially the vertical length of the turn-up. It operates in the same way and accomplishes the same results.

One of the main objects of the present invention and the principal purpose of the spreading means is to keep the cloth of the turn-up extended to the full width (vertically) or spread, or vertically supported, so that it must swing like a gate or door to get above or below the end of the knicker. This is the distinctive characteristic of the present invention. When this knicker is put on, the wearer steps into it just as he does into any pair of pants. The spreader is then in the position of Fig. 1, down. Next, the wearer "tucks" the turn-up 1 up, to the position of Fig. 4. The cloth, of course, is flexible and may be folded suitable to "tuck" up to the position of Fig. 4, as will be readily understood. It may, of course, be similarly turned down to the position of Fig. 1. But, the spreaders prevent the cloth rolling, or slipping, or otherwise dropping down by gravity.

It will be understood that any other suitable spreading means may be used which will substantially accomplish the same result and that any other suitable means may be used for maintaining the spreading means in operative position. It is meant to include all of these within this application.

As mentioned, one very important point of this invention is the simplicity of the adjustment of knicker length. To lengthen the knicker leg, it is only necessary to correspondingly shorten the spreaders. This allows a corresponding portion of the turn-up to slip down, as it would if there were no spreader. This lengthens the leg to a corresponding degree. Likewise, to shorten the leg, it is only necessary to substitute longer spreaders. It is believed that this will be obvious and readily understood and requires no illustration nor further description.

It might be mentioned here, that for men's knickers having a width of twenty inches at the end of the measurement, the turn-up is narrowed to sixteen inches, approximately, instead of fifteen. It has been proven that the approximate measurements of fifteen inches for boys and sixteen for men, is the most satisfactory.

Of course, the measurements, proportions, designs, and other details for ladies' knickers are considerably different, from the same for men's and boys'. Those differences are all well understood and need not be mentioned here, as they form no part of the present invention. Likewise, the various details of proportions, and construction of men's and boys' knickers are all well known and need no mention, and form no part of the present invention. This invention would be incorporated in ladies' knickers just as it is in boys' and men's.

It should be stated that the entire turn-up, when in the operative position of Fig. 4, is appreciably below the knee of the wearer, as worn, just as is the blouse portion or lower-leg fullness of every other knicker.

It is believed that the construction, operation and use of the invention will be clear from the preceding detailed description.

Many changes may be made in the construction, arrangement and disposition of the various parts of the invention, within the scope of the appended claims, and it is meant to include all such within this application wherein only one preferred form and several modifications have 10 been disclosed, purely as illustrations and with no thought or intention to in any degree limit the application thereby.

Having thus described my invention, what I claim and desire to secure by Letters Patent is:—

- 15 1. A knicker comprising a leg having a tapered turn-up portion, loops carried by said portion, and spreaders mounted in said loops and extending to the minimum diameter of said turn-up portion and adapted to maintain said portion spread.
- 20 2. A knicker comprising a leg having a tapered turn-up portion in continuation of one end, loops carried by said portion, and spreaders remov-

ably mounted in said loops and extending to the minimum diameter of said turn-up portion and adapted to maintain said portion spread.

3. A knicker leg having a flexible tapered turn-up section in continuation of its lower end and 5 having its lower edge diameter the minimum diameter of the knicker leg, loops carried by the inner face of said turn-up portion, and spreaders removably mounted in said loops, extending the full length of said turn-up portion and 10 extending to the minimum diameter thereof and adapted to maintain said portion spread at all times.

4. A knicker comprising a leg having a tapered turn-up portion in continuation of one end, a 15 plurality of spreaders for said turn-up portion and extending to the minimum diameter of said turn-up portion and adapted to maintain said portion spread, and means for removably securing said spreaders, each separately, to said turn- 20 up portion.
